UNITED STATES PATENT OFFICE.

PETER B. BRAZEL, OF CHEBOYGAN, MICHIGAN.

MACHINE FOR SHARPENING HORSESHOE-CALKS.

SPECIFICATION forming part of Letters Patent No. 659,388, dated October 9, 1900.

Application filed May 28, 1900, Serial No. 18,206. (No model.)

To all whom it may concern:

Be it known that I, PETER B. BRAZEL, a citizen of the United States, residing at Cheboygan, county of Cheboygan, State of Michigan, have invented a certain new and useful Improvement in Machines for Sharpening Shoe-Calks; and I declare the following to be a full, clear, and exact description of the same, such as will enable others skilled in the art to which it pertains to make and use the same, reference being had to the accompanying drawings, which form a part of this specification.

My invention relates to machines for sharpening horseshoe-calks, and has for its object the providing of a simple portable and cheap apparatus for the purpose of sharpening the calks without removing the shoe from the horse's foot; and this I attain by the mechanism arranged and combined as hereinafter described and claimed, reference being had to the accompanying drawings, in which—

Figure 1 is a perspective of the complete machine, showing the horse's foot in position for sharpening one of the heel-calks. Fig. 2 is a perspective on a somewhat larger scale of a portion of the same machine with a foot in position for sharpening the toe-calk. Fig. 3 is an enlarged detail vertical sectional view of the working portions of the machine without the sustaining framework and clearly showing its principle and mode of operation.

In the drawings, A represents a supporting-framework formed of two bars *a a*, united through a hollow standard B by bolts *b b*. The bars *a a* are spread, so as to form supporting or contact points with the floor at *a' a'*, and they are preferably united at their extremities by a wooden cross-bar *a²*. The opposite ends of the bars *a a* are curved downwardly and carry a traveling wheel A'. Thus the whole machine rests upon three points—*a' a'* and the traveling wheel A'—and is easy to transport and always rests when in position on a stable foundation. The framework A is made of sufficiently-strong bars of iron or steel to give the necessary rigidity to the structure. The hollow standard B is a heavy casting, within which is adjustably carried a compound upright C, made up of several pieces. Its height can be adjusted by means of a screw S, threaded in the bottom thereof

and revolvably fixed in a bottom block S', carried between the two bars *a a*, by rotating the screw by the hand-wheel. The compound bar C may be raised or lowered and rigidly fixed in any position by the impinging set-screw S². The compound bar C is made up of two side pieces *c c*, united at the top by a block C' and also at the bottom by a block *c²*. These blocks are recessed and carry hardened-steel dies D', being held therein by bolts or pins *d d'*, passing through the side pieces *c c*. A set-screw S³ is used as a means of longitudinal adjustment of the block D. The block D' 65 may be raised and slips passed in under it as a means of adjustment, if desired. It will be observed that between the side pieces *c c* and at the upper end of the compound bar C is left a mortise of peculiar shape, as shown in the 70 sectional Fig. 3. Pivoted in this mortise is a double cam-lever E', carrying cams *e e* of a proper shape to grasp and hold any conical surface inserted between the inclined lower and corrugated faces of the die D or the upper inclined cam-face of the die D'. This cam is held in position between the blocks D and D' by a strong through-pin F. An arm E' extends from the cam-head E, to which is pivoted the link G. Upon the rear side of the 80 compound bar C is formed a pair of brackets H, to which is pivoted a lever J by means of a pin K. This lever may be of any reasonable length, and to it is pivoted at g the link G. It will be readily seen that the oscillation of 85 the lever J will cause the jaws formed by the cam E to open and close with a drawing motion upon the part of the cam projections *e e* and that the combination of the levers and linkages form a compound lever of great 90 power.

As shown in Fig. 1, the compound standard C is cut out opposite the upper cam in order to facilitate the entrance of a toe-calk, as shown in Fig. 2. Pivoted upon the pin F is 95 a lever L, having two sides which grasp or inclose the compound standard C and which are formed of one piece having a peculiar shape, as shown in the drawings, the front loop M of which is adapted to grasp the toe of the hoof 100 and hold it firmly when the toe-calk is placed in between the jaws *e* and D. This lever L is continued by a single piece L', forming a foot-piece L², upon which the operator can

place his foot, at the same time manipulating the lever J by hand. A curved spring N controls the lever L L' and throws up its outer end and releases the clamp formed by M whenever pressure upon its outer extremity is withdrawn.

The mode of operation of this device is as follows: The machine is placed in convenient proximity to the shod animal. The foot with the shoe is lifted and placed so that, say, a toe-calk is inserted between the jaws e and D. The operator then places his foot upon the outer extremities L² of the lever L and holds the toe in that position, the lever J being raised when thus in position, and on depressing the lever J the calk is both drawn and compressed to any required degree ending with a sharp edge. On lifting the foot from the lever L² the spring N releases the toe and the shoe is withdrawn. The heel-calk is placed between the jaws e and D', as shown in Fig. 1, when the lifting of the lever J will perform the same operation upon the calk inserted that was performed upon the toe-calk. This operation is repeated until all the calks are sharpened as desired.

What I desire to claim is—

1. In a machine for sharpening shoe-calks, a portable frame, a vertical standard carried thereby, a cam located on said standard adapted to turn in a vertical plane, means for actuating the cam, a die having its working face approximately horizontal and extending inward from the side of said standard, whereby the calks of the shoe upon the hoof may be placed against said die, said die being fashioned to coöperate with the cam and held rigidly by the standard whereby the oscillation of the cam opens and closes a space between the die and the cam, thereby compressing and sharpening the calk, substantially as described.

2. In a machine for sharpening shoe-calks, a portable frame, a standard carried thereby, means for adjusting the standard, a cam located in a mortise in a standard, means for actuating the cam, a die fashioned to coöperate with the cam, and held rigidly by the standard whereby the oscillation of the cam

opens and closes a space between the die and the cam thereby compressing any substance inserted between them, and a lever L, pivoted to the standard and having a curved frontal portion on the short arm coöperating with the standard and adapted to hold the toe of a hoof, substantially as described.

3. In a machine for sharpening shoe-calks, a tripod framework carrying an adjustable standard, a guide for said standard within which the same is adapted to move, means for adjusting the height of the standard, a double cam operated within the standard, adjustable dies formed to and coöperating with either side of the cam, means whereby said cam operates by a lever adapted to reciprocate the reverse reciprocation of the lever operating either side of the cam alternately, substantially as described.

4. In a machine for sharpening shoe-calks, a portable frame, a standard carried thereby, a cam located upon said standard, means for actuating the cam, a die adapted to coöperate with the cam, and held rigidly by the standard whereby the oscillation of the cam opens and closes a space between the die and the cam thereby compressing any substance inserted between them, and a lever L, pivoted to the standard and having a curved frontal portion on the short arm coöperating with the standard and adapted to hold the toe of a hoof, substantially as described.

5. In a machine for sharpening shoe-calks, a portable frame, a standard carried thereby, a double cam operated within the standard, dies upon said standard adapted to coöperate one with one side of said cam to sharpen the toe-calk, and the other with the other side of said cam to sharpen the heel-calk, means whereby said cam operates by a lever adapted to reciprocate the reverse reciprocations of the lever operating either side of the cam alternately, substantially as described.

In testimony whereof I hereunto sign this specification in the presence of two witnesses.

PETER B. BRAZEL.
